SOUND CONDUCTING TUBE FOR
HEARING AIDS

Lillian D. Cates, Los Angeles, Calif.

Application March 12, 1948, Serial No. 14,500

11 Claims. (Cl. 181—22)

1

My invention relates to improvements in hearing aid apparatus, and particularly to an improved means for conducting sound to the ear by air conduction.

The present invention is an improvement over that described and claimed in my copending patent application, Serial No. 753,393 filed June 7, 1947. In that application I described and claimed hearing aid apparatus including a sound reproducing device having an electric cord associated therewith and a cord support in the form of a filamentary member shaped to fit the rear portion of the user's head. This member is designed to support the cord at a point adjacent the user's ear so that the sound reproducing device may be mounted in the ear and also to support another portion of the cord at a point at the back of the user's head so that the remainder of the cord is led downwardly from that point beneath the wearer's garments and thence into communication with a microphone or sound pick-up device, which is usually mounted on the chest.

By employing such a cord support it is possible for a lady to lead the cord from the sound pick-up device to the sound reproducing device for use, without employing hairpins, bobby pins or the like, and with the cord well concealed.

According to the present invention, a sound conductor, preferably in the form of a tubular member, is shaped to encircle the portion of the user's head between the affected ear and the back of her head. The sound reproducing device is connected to a point of the sound conductor near the back of the head and an ear mold fitted to the mouth of the auditory canal is connected with the forward portion of the sound conductor in order to lead sound from the conductor into the ear. The sound conductor mentioned is preferably composed of stiff material, and the ear mold is connected thereto through a resilient tube.

This new type of hearing aid apparatus combines the advantage of being completely concealable beneath a lady's hair and the advantages of being less cumbersome and more convenient to use, partly because of the light-weight and small size of the ear mold, and partly because of the elimination of the necessity of leading electrical conductors from the back of the head to the affected ear.

The foregoing and other features and advantages of my invention will appear more fully from the reading of the following detailed description of two embodiments of the present invention taken in connection with the accompanying drawing which illustrates them, and in which:

2

Figure 1 is a perspective view of the rear of the head of a lady using one embodiment of the invention;

5 Figure 2 is a perspective view of the hearing aid apparatus alone;

Figure 3 is a cross-sectional view of the connector;

Figure 4 is a rear view of the connector;

10 Figure 5 is an enlarged detailed view partly in cross-section of one end of the hearing aid apparatus of Figure 1;

Figure 6 is a perspective view of a second form of the hearing aid apparatus; and

15 Figure 7 is a perspective view of the rear of the head of a lady wearing the second form of the apparatus.

In Figures 1 to 5 inclusive there is illustrated hearing aid apparatus embodying the features of the present invention and comprising a main sound conductor 10 which includes a rear portion 12 shaped to encircle the back of a lady's head and also including two upwardly extending arms 14 which terminate in downwardly directed forwardly extending hooks 16. The entire main conductor 10 is shaped to conform to the back of the user's head when supported thereon by resting the hooks 16 upon the upper portions of the user's ears. For this purpose the main conductor 10 is preferably composed of silver or a light-weight aluminum or magnesium alloy, and is generally preformed into the general configuration required, but adapted to be readily and permanently altered in shape in order to fit the individual user's head comfortably.

20 35 The main conductor 10 may be in the form of two branch tubes 18 which lead rearwardly from the respective ears of the user to the back of the user's head where they are joined by means of a coupling 20. The coupling may be in the form of

40 40 a small flat cylindrical or disc-shaped body member having a central cavity 22 which communicates with two radially extending bores 24 in which the rear ends of the branch tubes 18 are pressed-fit or otherwise securely attached.

45 45 A coaxial passage 26 in the rear face of the coupling 20 is employed for introducing sound signals into the cavity 22 from which it is thence conducted through one or both of the branch tubes 18 to one or both of the user's ears. The outer end of the coaxial passage 26 is defined,

50 50 at least in part, by means of a female connector 28 of the snap type which serves to clasp the projecting male portion 30 of a conventional sound reproducing device 32.

55 The sound reproducing device 32 is of a type which converts into sound waves, electrical signals

carried thereto through electrical conductors 34 from a microphone (not shown). These sound waves enter the cavity 22 and are then distributed through the branch tubes 18 to the one ear or both, as the case may be.

An auxiliary conductor 40 is connected at one end to a nipple 14 which projects outwardly from the main conductor 10 at a point behind the affected ear and terminates at the other end in an ear mold 42 which is shaped to fit snugly within the mouth of the auditory canal of the user's ear. The ear mold 42 is provided with an orifice 43 which connects the auxiliary tube 40 to the auditory canal. Thus the auxiliary conductor 40 and the ear mold 42 form a branch passage which provides an air conduction path from the cavity 22 within the coupling to the auditory canal of the affected ear.

The foremost ends of the main conductor 10 may be closed, such as by seals formed directly therein, or the branch conductor 18 to which the auxiliary conductor 40 is connected may be closed by means of a plug 44 on the forward side of the nipple 41. Also, a plug 46 may be mounted within the other branch tube 18 if it is not being employed to conduct sound to the other ear.

In order to effect maximum concealment of this hearing aid apparatus, the most forward portions of the branch tubes 18, and the auxiliary conductor 40, and the ear mold 42 are preferably formed of flesh-colored material, or at least covered with a flesh-colored coating, and the remainder of the apparatus including the rear portions of the branch tubes 18, the entire coupling 20, the sound reproducing device 32, the electrical conductors 34 are formed of material the same color as the hair of the user, or is at least covered with a coating of such color.

In an alternative form of my invention illustrated in Figures 6 and 7, the auxiliary conductor 40 is connected to a forward open tip of a branch tube 18. This is preferably accomplished by enlarging the tip 50 slightly, and slipping one end of the auxiliary conductor 40 over it.

In the latter form of the invention, the need for a nipple 41 is eliminated and the entire structure of the forward portion of the hearing aid apparatus greatly simplified. In this form of the invention the entire main conductor is preferably of the color of the user's hair, while the auxiliary conductor 40 and the ear mold 42 are flesh-colored.

In both forms of the invention described above, the branch tubes 14 are preferably composed of relatively stiff material such as metal and the auxiliary tube 40 is preferably composed of a resilient or flexible material such as rubber-like or plant plastics.

It is to be noted that the electrical conductors 34 may be led through the tube from the rear opening to the forward opening in accordance with the principles set forth in my aforementioned copending application. Accordingly, to the extent the hearing aid apparatus of this application also employs a hollow tubular member, it is to be considered a continuation-in-part of my prior filed copending application.

From the foregoing description of my invention it is clear that I have provided improved hearing aid apparatus of compact, inexpensive construction which may be readily secured in place beneath a lady's hair without the use of hairpins or bobby pins and with all parts thereof concealed. Besides being easily concealed and being worn readily without interference with the

combing of a lady's hair, this hearing aid apparatus is very comfortable to use.

While the invention has been described more or less in detail with reference to two particular embodiments thereof, it is to be understood that many changes may be made therein without departing from the true spirit and scope of my invention. In particular, it is to be understood that in the embodiment of the invention illustrated in Figure 1, the auxiliary sound conductor may be carried over the ear rather than under it. Also, in particular, it is to be understood that while the support member which encircles the head has been described as formed of stiff tubular sections on both sides of the coupling, it might be formed of a flexible tubular section on one side and a wire member on the other side. In fact, if desired the tubular section in this case might even be flexible and terminate at the ear mold. It is also to be understood that the main conductor may be made of other materials such as suitable thermo-plastics and any flexible member is preferably made of a flexible plastic. Reference is therefore to be had to the appended claims for a definition of the limits of my invention.

I claim:

1. In hearing aid apparatus of the air-conduction type, a stiff tubular member shaped to fit the rear portion of a user's head and means for holding one end thereof adjacent the user's affected ear and the other end thereof at the back of the user's head, said member including a rear opening at the back of the user's head and a front opening adjacent the user's affected ear and in the tip of said tubular member, an ear mold adapted to fit in the mouth of an auditory canal of said affected ear and having an orifice therein adapted to communicate with said canal, and a flexible tubular member connected to conduct sound from said front opening to said orifice.

2. In hearing aid apparatus of the air-conduction type, a stiff tubular member shaped to encircle the rear portion of the user's head, said tubular member being formed with hooks for hooking over the top portion of the user's ears, said member including a rear opening at the back of the user's head and a front opening adjacent one ear of the user.

3. Hearing aid apparatus as defined in claim 2 in which said rear opening is defined by a female connector adapted to clasp the male part of a conventional hearing aid sound reproducing device.

5. Hearing aid apparatus as defined in claim 3 in which said front opening is in the tip of said tubular member.

5. Hearing aid apparatus as defined in claim 3 comprising means for blocking sound conduction in said tubular member from said rear opening toward the other ear.

6. Hearing aid apparatus as defined in claim 4 comprising an ear mold adapted to fit in the mouth of an auditory canal and having an orifice therein adapted to communicate with said canal, and a flexible tubular member connected to conduct sound from said front opening to said orifice.

7. In hearing aid apparatus of the air-conduction type for use by ladies, a tubular structure provided with a forward opening and a rearward opening, at least the forward portion of said structure being flexible, means for mounting a hearing-aid sound-reproducing device at

said rearward opening and in sound communication therewith, an ear mold adapted to fit in the mouth of an auditory canal of the user's affected ear and having an orifice therein adapted to communicate with said canal, said ear mold being connected to conduct sound from said front opening to said orifice, and means terminating adjacent the user's other ear for holding said tubular structure securely in position along a line adjacent the user's head with said forward opening adjacent said affected ear and said rearward opening displaced rearwardly therefrom, the spacing of said forward opening and said rear-opening being such that said sound-reproducing device and any electric cord leading there-to may be concealed beneath a lady's hair when said tubular structure is in such position.

8. Hearing aid apparatus as defined in claim 7 wherein said last mentioned means includes a hook member adapted for hooking over said other ear, said hook member being connected to the rear portion of said tubular structure.

9. In hearing aid apparatus of the air-conduction type, a stiff tubular member shaped to fit the rear portion of a user's head, and means for holding one end thereof adjacent the user's affected ear and the other end thereof at the back of the user's head, said member including a front opening adjacent the user's affected ear and a rear opening at the back of the user's head, an ear mold adapted to fit in the mouth of an auditory canal and having an orifice therein adapted to communicate with said canal, and a flexible tubular member connected to conduct sound from said front opening to said orifice.

10. In hearing aid apparatus of the air-conduction type particularly suitable for use by ladies, a tubular member shaped to fit the rear portion of a user's head, means for holding one end thereof adjacent the affected ear and the other end adjacent the back of the user's head, said tubular member having a passage therein extending from a front point adjacent the user's

affected ear to a rear point at the back of the user's head, a sound reproducing device connected in sound conducting relationship with said passage at said rear point, an ear mold adapted to fit in the mouth of the auditory canal of a user's affected ear and having an orifice therein adapted to communicate with said canal, and a flexible tubular member connected to conduct sound from said front point to said orifice, whereby said entire hearing aid may be concealed from view while in use by a lady.

11. In hearing aid apparatus of the air-conduction type particularly suitable for use by ladies, a tubular member shaped to encircle the rear portion of a user's head, said tubular member being provided with hooks for hooking over the top portion of the user's ears, said tubular member having a passage therein extending from a front point adjacent the user's affected ear to a rear point at the back of the user's head, a sound reproducing device connected in sound conducting relationship with said passage at said rear point, an ear mold adapted to fit in the mouth of the auditory canal of the user's affected ear and having an orifice therein adapted to communicate with said canal, and a flexible tubular member connected to conduct sound from said front point to said orifice, whereby said entire hearing aid may be concealed from view while in use by a lady.
